RATE OF RISE CIRCUIT CONTACT
OPERATING DEVICEJulian F. Rowe and Jean E. Rowe,
Stewart Manor, Long Island, N. Y.

Application August 10, 1944, Serial No. 548,916

15 Claims. (Cl. 200—140)

The present invention relates to circuit contact operating devices which respond in a desired predetermined manner to certain rates of rise of temperature.

A general object of the invention is the provision of a simplified but rugged and easily manufactured rate of rise circuit contact operating device characterized by a chamber containing a body of displaceable liquid and electrical circuit contact operating means buoyed by the liquid, which is efficient in operation and readily maintained and provides for simple adjustment for control of sensitivity, ready inspection of the interior and easy removal of parts for servicing.

A more specific object of the invention is to provide an efficient rate of rise circuit contact operating device in which at least two intercommunicating chambers are partially filled with a non-conducting spark-quenching liquid with simple means buoyed by the liquid in one chamber for effectively operating or affecting in a simple manner electrical circuit contacts when sudden pressure changes of a predetermined nature are applied to a surface of the liquid from a so-called "rate of rise" detection system to cause inter-chamber flow of liquid.

A further object of the invention is the provision of such device which is readily adapted to use as a control in a fire detecting or alarm system or the electrical system of an irregularly operable light display, and the like; which is composed of a minimum number of parts readily assembled in a manner whereby they cooperate in an unusual manner to support and properly position each other while providing a plurality of simple means independently or cooperatively governing sensitivity assuring ready and easy obtainment of unusually fine adjustment thereof; and which may be operated in a manner to assure efficient spark-quenching while avoiding undue corrosion and destruction of parts.

Other objects of the invention will in part be obvious and will in part appear hereinafter.

The invention accordingly comprises the features of construction, combination of elements and arrangement of parts, which will be exemplified in the construction hereinafter set forth and the scope of the invention will be indicated in the claims.

For a fuller understanding of the nature and objects of the invention, reference should be had to the following detailed description taken in connection with the accompanying drawing, in which:

Fig. 1 is an elevational section, with parts

broken away, of an embodiment of the device of the present invention;

Fig. 2 is a sectional view taken along line 2—2 of Fig. 1, showing a top plan view of the casing of the unit shown in Fig. 1;

Fig. 3 is a transverse sectional view of that embodiment, taken along line 3—3 of Fig. 1;

Figs. 4 and 5 are views similar to Fig. 3, with parts broken away, taken respectively along lines 10 4—4 and 5—5 of Fig. 1; and

Fig. 6 is a plan view to reduced scale of a modified form of top chamber spacer.

Referring to the drawing like numerals identify like parts throughout. An embodiment of 15 the invention, as shown in Fig. 1, preferably comprises an inner tube 10 which may desirably be formed of any suitable transparent material for purposes of inspection, such as glass, and an outer tube 11 telescoped therewith and preferably formed of similar material. The inner tube 10 may be of any suitable shape, such as circular, elliptical, etc., in cross-section, and is substantially closed at the top 12 with the latter provided with a hollow neck 13 having an airtight connection with a passage member such as the tube 14, communicating with an expansion chamber of any suitable type. The tube 14 may be extended as indicated to provide the expansion chamber, and may be desirably of flexible construction so as to be manipulated in any suitable manner, such as for the purpose of extending it around a room when the device is used as a fire detecting system control. The tube 14 is preferably provided near or adjacent the instrument 30 35 with a bleed-off spout 15 which is preferably restricted in any suitable manner, such as by a plug 16 of any suitable filler material, such as soft twine, to restrict the rate of bleed-off flow of fluid from the expansion chamber in a controlled manner and to provide for ready sensitivity adjustment by the degree of packing of the filler 16. With the tube 15 formed of readily severable plastic material and with an elongated filler plug 16 employed decrease of the degree of 40 45 restriction of flow of fluid therethrough may selectively be accomplished in an easy manner by cutting off a portion of the end thereof to foreshorten the length of the passage restriction. If desired the end of tube 15 may be fitted with a breather hood to serve as a dust guard.

The outer tube 11 is closed at the bottom 17 as shown and is open to the atmosphere at or near its top, or above liquid level, and preferably is provided with a top flange 18 for suitably loosely centering it and spacing it from a sur-

rounding dust guard or protective casing tube 19 also preferably of any suitable transparent material. The outer tube 11 is desirably supported at its bottom 17 by any suitable means to permit elevational adjustment thereof. This means may comprise a supporting block 20 which may be raised or lowered by a manual screw 21 threaded into any suitable supporting base plate 22 upon which the casing tube 19 rests.

The casing is preferably completed by a cap member 23 resting upon the top edge of the casing tube 19 and tie bolts 24-24 may be employed to hold the casing tube 19, support plate 22, and cap 23 in their assembled positions. Obviously, if desired the casing tube 19 may be held in position between the base plate 22 and cap 23 by any suitable mounting means in lieu of tie bolts 24-24, such as by a panel for suspension of the unit on a wall, to which panel the base plate and cap may be affixed in any suitable manner, such as by screws, etc. The cap 23 may be provided with any suitable means for support of the instrument, such as an integral flange 25, for mounting the instrument to a wall-supported panel or the like. The cap 23 preferably is provided with a central aperture surrounded by a boss 26 over which is snapped a flexible sleeve 27 which suitably anchors the tube 14 in position.

The inner tube 10 is suitably aligned and supported by means of a top spacer member 28 which, as shown in Fig. 4, may comprise a disc of suitable insulating material, preferably somewhat resilient, having a substantially centrally located aperture snugly receiving the neck 13 and with its peripheral edge snugly engaged at 29 with the inner walls of the outer tube 11, centering or properly aligning the inner tube 10 within the outer tube, providing a shock absorber therebetween, and serving to prevent undesirable floating of tube 10. The top spacer 28 is also provided with a plurality of passages or holes 30-30 which may be in the form of notches in the periphery thereof, as shown in Fig. 4, for reception and passage of hanger wires 31-31 which, being formed of suitable metallic material such as copper, also serve as conductors in the electrical circuit. Three such wires may be provided, if it is desired, to operate two signal devices, such as a buzzer and a bell from the single control, with one wire being common to both circuits of the two signal devices. Tube 11 should have communication with the atmosphere above the level of the liquid therein and this may be provided as a passage or passages through spacer 28, such as by notches 30-30, of sufficient dimension to permit pressure of fluid in the outer chamber to be equalized to atmospheric pressure quite rapidly.

It may be desired to have the top spacer 28 form a tight seal in the mouth of the outer tube 11 in and about the supporting wires 31-31, and in such case, as proposed in Fig. 6, the top spacer 28 may be formed of sponge rubber with undersized notches 130-130 formed in the periphery thereof snugly to receive the wires 31-31. That embodiment of the top spacer may be provided with a plurality of apertures 32-32 of predetermined dimension for regulation of escape of fluid from or into the outer tube 11 at its top or above the level of liquid in that tube.

A bottom spacer member 33 is positioned within the outer tube 11 near the bottom thereof, and when it is desired to provide for relative longitudinal adjustment of the tubes 10 and 11, the periphery of spacer 33 may be substantially snugly fitted to the inner walls of the outer tube 11, but

with sufficient elasticity or slight clearance to permit relative sliding movement. Of course in such case the periphery of the top spacer 28 should also have a like provision for such sliding movement with respect to the inner walls of the outer tube 11. Such relative sliding mount of the tubes 10 and 11 may be provided for the purpose of varying the level of the surface 34 of the body of liquid 35 which partially fills the two chambers formed by the inner tube 10 and by the space between the outer tube 11 and such inner tube 10. Such structure also permits ready removal of the outer tube 11 for servicing, such as change of liquid, cleaning, etc.

The bottom spacer 33, as shown in Fig. 5, is provided with a central aperture 36 which is in the shape of a cloverleaf to accommodate a cluster of the supporting circuit wires 31-31 with their surrounding flexible sleeves of insulation 37-37. The spacer 33 is also provided with peripheral notches 38-38 through each of which passes one of the support wires 31 with its surrounding insulating sleeve 37. The spaces 33 also supports the bottom edge of the inner tube 10 and is preferably provided for that purpose with a circumferential groove 39 to receive that edge, and likewise acts as a shock absorber between tubes 10 and 11. The bottom spacer 33, which provides the partition between the inner and outer chambers, is provided with passage means to permit flow of liquid between said chambers. Such means may be a plurality of grooves 40-40 which, by proper dimensioning, may be utilized to control the rate of flow of liquid between the inner and outer chambers.

As shown in Fig. 1 the support wires 31-31 are extended down between the inner tube 10 and the outer tube 11 and, with their surrounding insulating sleeves 37-37, are led through the notches 38-38 in the bottom spacer 33 and are then turned back upon themselves to extend through the central aperture 36 up into the inner chamber. In the inner chamber the cluster of support circuit wires 31-31 may, if desired, be provided with a suitable insulating and tying means 41 which may comprise a short sleeve of insulating material about each wire 31 with these sleeves bundled together by means of a cord or the like. Upwardly beyond the bundling and tying means 41 the circuit support wires 31-31 are provided with terminal portions 42-42 which, as shown in Fig. 1, may be spread radially to provide a seat for the circuit closing means, hereinafter described, and to assure its interception as it descends. The terminal portions 42-42 are preferably so shaped as to engage or substantially engage the inner walls of the inner tube 10 to provide for proper relative centering or alignment of the parts and additionally, if desired, to provide a friction grip to aid in preventing floating displacement of the inner tube 10.

The support circuit wires 31-31 are suitably suspended from any desired means, such as anchoring means mounted on or in the cap 23. Such anchoring means may comprise a pair of bolts 43, 43 and a relatively shorter bolt 44 of similar construction, except for their relative lengths. As shown in Fig. 3 the elongated bolts 43, 43 may each be surrounded by a sleeve 45 seated in a bore extending through the bracketing flange 25 and a boss 46 in the cap 23. The bolt 44 is likewise surrounded by a sleeve 47 which extends through a hole in the cover 23 and its bracketing flange 25. Each of the bolts 43, 43 and 44 is preferably provided with an aperture extending trans-

versely through its inner end to receive one of the support wires 31—31. Each of the outer ends of the bolts 43, 43 and 44 are provided with elongated slots 48—48, each of which is adapted to receive an external circuit wire 49. A nut 50 on each of the bolts completes the anchorage assembly and with the wires 31—31 and 49—49 extending through their respective apertures, tightening up of the nuts 50—50 will cause the sleeves 45, 45 and 47 to clamp the wires in position.

The non-conducting liquid 35, which partially fills the chambers provided within the inner tube 10 and between the inner tube 10 and the outer tube 11, is of a well-known type used in oil circuit-breakers or switches and has high dielectric strength, high flash point, non-gumming and non-volatile qualities, and is of a selected specific gravity which will obtain for the user a desired rate of flow under certain pressure conditions in a particular device of the invention. This body of non-conducting liquid buoys the contact operating means which may be a float of any desired type located in either chamber and associated with suitable means to operate contacts or, as preferred, may be a float of conducting material such as a hollow metal ball 51, or a hollow ball coated with conducting metal, located within the inner tube 10. The float 51 should have sufficient weight so that it submerges in the non-conducting liquid to a sufficient depth assuring circuit make-and-break below the surface of the liquid for efficient spark quenching and exclusion of oxygen during switching operations efficiently to eliminate fire hazard and to assure long life of contact surfaces. Preferably the float or ball 51 is of a diameter slightly less than the inside diameter of the inner tube 10, but greater than the spacing between the contacts 42—42 at their nearest approach, and greater than the space between adjacent contacts and also any space between such contacts and walls of the float-containing chamber. The employment of a float ball assures efficient making and breaking of the circuits at the contacts 42—42 regardless of the number thereof, such as three shown in the embodiment of the drawing. Further, as the level of the non-conducting liquid rises and lowers in the inner tube 10, in response to pressure changes produced in the expansion chamber, the ball 51 will roll evenly up and down the inner walls thereof with a minimum of surface tension.

Preferably the base plate 22 of the casing structure is provided with a breather hole 52 for communication between the atmosphere and the interior of the casing. If desired the flange 18 of outer tube 11 may, instead of or in addition to having some clearance with respect to casing tube 19, be provided with one or more notches, such as that shown at 53, or the like, to assure cooperative communication between atmosphere and the interior of the outer chamber.

In operation, when the embodiment of the invention shown in the drawing is employed, for example, in a fire detecting system with two alarm circuits being connected to the three terminal bolts 43, 43 and 44, and with one thereof serving as a common conductor in both circuits, the expansion chamber such as that provided by elongated, flexible tubing 14 may be suitably arranged around a room in any desired advantageous location. Slow rates of change of temperature in the room tend to cause slow expansion or contraction of air in the tube 14, as the case may be,

but such slow changes in pressure are concurrently offset by seepage of air through the bleeder tube 15 and do not affect the switch herein described. However, when unusual rates of rise of temperature are caused by any unusual conditions such as a fire, rapid expansion of the air in tube 14 will increase pressure more rapidly than air can pass through breather tube 15, and this would result in the application of pressure to the surface of the liquid in the inner-chamber 10 which is sufficient to cause flow of liquid from the inner chamber through passages 40—40 into the outer chamber, lowering the level of liquid in chamber 10 and permitting the float or ball 51 to fall into contact with the circuit contacts 42—42 thereby closing the circuits. It will be understood that operation of the device is not dependent upon the employment of only a single body of liquid in the two chambers and a body of air in the expansion chamber since obviously any expansible fluid medium may be used in the expansion chamber as desired and this may, if desired, apply pressure to the surface of the liquid, as described, directly or indirectly through an intermediate medium such as another body of immiscible liquid, etc., all as will be apparent to those skilled in the art. For example, the main body of liquid 35 may be water with a body of oil floated on the top thereof in the float chamber, with the body of oil being of sufficient volume to assure circuit making-and-breaking in the oil.

Sensitivity control or adjustment thereof may be accomplished by any one or more of certain features described above. Perhaps the more important of these is the degree of packing of the filler 16 in the breather tube 15, i. e., the amount of constriction thereof, which governs the rate of flow of fluid from and to the expansion chamber. This in turn determines the rate of expansion, or construction as the case may be, at which sufficient pressure change is developed in a liquid chamber to cause such alteration of the level thereof as to affect circuit operating means. The specific gravity of the liquid and size of inter-chamber passages will also have a bearing on the sensitivity of the device; as will also the freedom with which liquid is permitted to enter or leave the storage chamber, such as the freedom with which the liquid is permitted to displace fluid or air therein. Further, adjustment of the level of liquid in the float-containing chamber has a bearing on the sensitivity since by that means the distance between the normal position of the float and the position at which it affects the electrical circuits can readily be altered to change the conditions necessary to circuit-operation of the device.

It is to be understood that although inter-chamber flow may be provided only by means of grooves 40—40 in the lower spacer member 33, there may be used advantageously instead or cooperatively apertures such as check holes in the walls of the inner tube 10 at the minimum level to which the surface of the liquid therein is to be depressed. The advantage of this modification lies in the assurance of sub-surface contact in the operation of the switch. Although in the embodiment shown in the drawing the contact-operating float is shown in the chamber in which pressure variations are caused by a rate of rise detection system to displace or vary the amount of liquid therein, it is obvious that the float may be, if desired, located in the other or storage chamber either to close circuits contacts as the float rises therein, or to break a signal circuit below

liquid surface as such float rises. Further, the float need not, though it preferably does, operate contacts in the float chamber but may, if desired, move an operating member which in turn may externally affect circuit contacts.

As suggested above the device of the present invention may also be employed for purposes other than in the control of fire detecting systems. For example, it may be employed as a control for irregular switching of circuits of display or advertising lighting devices with the circuit wires thereof connected to relay means for heavy current switching and with the tube constituting the expansion chamber coiled up within the housing of the device, suitably connected to a bulb in the display circuit, and with the employment of suitable draft means or guards to cause irregular cooling of the expansion chamber.

It will thus be seen that the objects set forth above are efficiently attained, and since certain changes may be made in the above construction and different embodiments of the invention could be made without departing from the scope thereof, it is intended that all matter contained in the above description or shown in the accompanying drawing shall be interpreted as illustrative and not in a limiting sense.

It is also to be understood that the following claims are intended to cover all of the generic and specific features of the invention herein described, and all statements of the scope of the invention which, as a matter of language, might be said to fall therebetween.

Having described our invention, what we claim as new and desire to secure by Letters Patent is:

1. A rate of rise circuit contact operating device comprising a liquid container having at least two chambers, a non-conducting liquid partially filling the chambers, communicating means between the chambers located below the surface of said liquid and constituting the only means of communication between said chambers, electrical circuit contacts, means for affecting the electrical circuit contacts buoyed by the liquid, and means for applying sudden pressure changes from a rate of rise detection system to the surface of the liquid in one chamber to cause displacement thereof.

2. A rate of rise circuit contact operating device comprising a liquid container having at least two chambers, a non-conducting liquid partially filling the chambers, a body of immiscible fluid completing the filling of one chamber and adapted to apply pressure to the liquid in the chamber to cause displacement thereof, a partition segregating said chambers above the liquid surface but provided with communicating means between said chambers below said liquid surface means for applying sudden pressure changes from a rate of rise detection system to the fluid, electrical circuit contacts in one chamber, and means buoyed by the liquid for affecting the electrical circuit contacts when the liquid is displaced.

3. A rate of rise circuit contact operating device comprising a liquid container having at least two chambers, a non-conducting liquid partially filling the chambers, means for segregating said chambers above the liquid surface, communicating means between the chambers below said liquid surface, means for applying sudden pressure changes from a rate of rise detection system to the surface of the liquid in one chamber to cause displacement thereof, electrical circuit contacts in that chamber immersed in said liquid when said circuit is broken, and means buoyed by the

liquid for affecting the electrical circuit contacts when the liquid is displaced.

4. A rate of rise circuit contact operating device comprising a liquid container having at least two chambers, one of said chambers having an air space freely communicating with the atmosphere and the other chamber having a fluid space confined against free communication with the atmosphere, a non-conducting liquid partially filling the chambers, communicating means between said chambers located beneath the surface of said liquid, a body of immiscible fluid completing the filling of one chamber and adapted to apply pressure to the liquid in the chamber to cause displacement thereof, means for applying sudden pressure increases from a rate of rise detection system to the fluid, electrical circuit contacts immersed in the liquid in that chamber, and means buoyed by the liquid for affecting the electrical alarm circuit contacts when the liquid is displaced.

5. A rate of rise circuit contact operating device comprising a liquid container having at least two chambers, a non-conducting liquid partially filling the chambers, communicating means between the chambers located beneath the surface of said liquid and constituting the only communication between said chambers, regulating means for controlling the rate of flow of liquid between the chambers, a body of immiscible fluid completing the filling of one chamber and adapted to apply pressure to the liquid in the chamber to cause displacement thereof, means for applying sudden pressure increases from a rate of rise detection system to the fluid, electrical circuit contacts immersed in the liquid when said circuit is broken, and means buoyed by the liquid for affecting the electrical circuit contacts when the liquid is displaced.

6. A rate of rise circuit contact operating device comprising a liquid container having at least an inner and an outer chamber of transparent material, a non-conducting liquid partially filling the chambers, communicating means between the chambers located wholly beneath the surface of said liquid and constituting the only communication between said chambers, a body of immiscible fluid completing the filling of the inner chamber and adapted to apply pressure to the liquid in the chamber to cause displacement thereof, means for applying sudden pressure increases from a rate of rise detection system to the fluid, electrical circuit contacts immersed in the liquid when said circuit is broken, means buoyed by the liquid for affecting the electrical circuit contacts when the liquid is displaced to a certain critical level, and means for regulating liquid displacement to the critical level.

7. A rate of rise circuit contact operating device comprising a liquid container having at least two chambers, a non-conducting liquid partially filling the chambers, communicating means between the chambers located beneath the level of said liquid and constituting the only means of communication therebetween, a body of immiscible fluid completing the filling of one chamber and adapted to apply pressure to the liquid therein to cause liquid displacement, means for applying sudden pressure increases from a rate of rise detection system to the fluid, electrical circuit contacts immersed in the liquid when said circuit is broken, means buoyed by the liquid for closing the electrical circuit contacts when the liquid is displaced from an initial level to a cer-

tain critical level, and means for adjusting the initial level of the liquid.

8. A rate of rise circuit contact operating device comprising an outer chamber, a tube positioned in said outer chamber and constituting an inner chamber, means closing the bottom of said tube and provided with a passage for inter-chamber communication, a body of non-conducting liquid partially filling said chambers and covering said passage, a float in said inner chamber buoyed by said liquid, a rate of rise means connected to the upper portion of said tube and containing an immiscible fluid adapted to apply pressure to the surface of the liquid in said chamber, and contacts for an electrical circuit controlled by movement of said float.

9. A rate of rise circuit contact operating device comprising an outer chamber; a tube positioned in said outer chamber and constituting an inner chamber; a body of non-conducting liquid partially filling said chambers; means for spacing the upper part of said tube from the walls of said chamber; means for closing the bottom of said tube, spacing it from the walls of said outer chamber, having openings to allow circuit wires to enter the bottom of said tube and to pass between the tube and the walls of said outer chamber, and having a passage for inter-chamber communication; a float in said inner chamber buoyed by said liquid; a rate of rise means connected to the upper portion of said tube and containing an immiscible fluid adapted to apply pressure to the surface of the liquid in said tube; and contacts for an electrical circuit controlled by movement of said float.

10. A rate of rise circuit contact operating device comprising an outer chamber; a tube positioned in said outer chamber and constituting an inner chamber; a body of non-conducting liquid partially filling said chambers; means for spacing the upper part of said tube from the walls of said chamber; means for closing the bottom of said tube, spacing it from the walls of said outer chamber, having openings to allow circuit wires to enter the bottom of said tube and to pass between the tube and the walls of said outer chamber, and having a liquid passage for inter-chamber communication; a float in said inner chamber buoyed by said liquid; a rate of rise means connected to the upper portion of said tube and containing an immiscible fluid adapted to apply pressure to the surface of the liquid in said tube; contacts for an electrical circuit controlled by movement of said float; and means for adjusting the relative heights of the inner and outer chambers.

11. A rate of rise circuit contact operating device comprising an outer chamber of transparent material, a tube of transparent material positioned in said outer chamber in adjustable relation thereto and constituting an inner chamber, means closing the bottom of said tube and provided with a passage for inter-chamber communication, a body of non-conducting liquid partially filling said chambers and covering said passage, a float in said inner chamber buoyed by said liquid, a rate of rise means connected to the upper portion of said tube and containing an immiscible fluid adapted to apply pressure to the surface of the liquid in said tube, and contacts for an electrical circuit controlled by movement of said float.

12. A rate of rise circuit contact operating device comprising an outer chamber; a tube of insulating material positioned in said outer cham-

ber and constituting an inner chamber; a body of non-conducting liquid partially filling said chambers; means for spacing the upper part of said tube from the walls of said chamber; means for closing the bottom of said tube, spacing it from the walls of said outer chamber, and having a liquid passage for inter-chamber communication; circuit wires passing down between said tube and the walls of said chamber and through said bottom spacer to support the latter and said tube, said wires terminating in circuit terminal portions in said tube; a rate of rise means connected to the upper portion of said tube and containing an immiscible fluid adapted to apply pressure to the surface of the liquid in said tube and depress the level thereof by displacement; and an electrically conducting float in said tube buoyed by the liquid for closing an electrical circuit connected to said wires when the level of said liquid is depressed.

13. A rate of rise circuit contact operating device comprising an outer chamber, a tube positioned in said outer chamber and constituting an inner chamber, means providing substantially free communication between the atmosphere and the upper portion of said outer chamber, means confining the upper portion of the inner chamber against free communication with the atmosphere, means closing the bottom of said tube and provided with a passage for inter-chamber communication, a body of non-conducting liquid partially filling said chambers, an electrically conducting float in said inner chamber buoyed by said liquid, a rate of rise means connected to the upper portion of said tube and containing an immiscible fluid adapted to apply pressure to the surface of the liquid in said tube, electrical circuit contacts mounted in said tube for contact by said float upon depression of the liquid and immersed in the latter when said circuit is broken, and means for adjusting the relative heights of the inner and outer chambers.

14. A rate of rise circuit contact operating device comprising an outer chamber of transparent insulating material, a tube of transparent insulating material positioned in said outer chamber in adjustable relation thereto and constituting an inner chamber, a body of non-conducting liquid partially filling said chambers, means for spacing the upper part of said tube from the walls of said outer chamber; means for closing the bottom of said tube, spacing it from the walls of said outer chamber, and having a liquid passage for inter-chamber communication; circuit wires passing between the tube and the walls of said outer chamber through said bottom spacer and up into said tube, said wires supporting said spacer and tube and said wires being connected to terminal means beneath the normal surface of the liquid; an electrically conducting float in said inner chamber buoyed by said liquid for circuit-closing contact with said terminal means upon depression of the liquid surface from an initial level; a rate of rise means connected to the upper portion of said tube and containing an immiscible fluid adapted to apply pressure to the surface of the liquid in said tube for depression thereof; and means for adjusting the relative heights of the inner and outer chambers for altering the initial liquid level.

15. A rate of rise circuit contact operating device comprising an outer chamber; a tube of insulating material positioned in said outer chamber and constituting an inner chamber; a body of non-conducting liquid partially filling said

chambers; means for spacing the upper part of said tube from the walls of said chamber; means for closing the bottom of said tube, spacing it from the walls of said outer chamber, and having a liquid passage for inter-chamber communication; circuit wires passing down between said tube and the walls of said chamber and through said bottom spacer to support the latter and said tube, said wires terminating in circuit terminal portions in said tube frictionally gripping the inner walls thereof beneath the normal surface of

10

the liquid; a rate of rise means connected to the upper portion of said tube and containing an immiscible fluid adapted to apply pressure to the surface of the liquid in said tube and depress the level thereof by displacement; and an electrically conducting float in said tube buoyed by the liquid for closing an electrical circuit connected to said wires when the level of said liquid is depressed.
